UNITED STATES PATENT OFFICE.

CHARLES F. ROPER, OF HOPEDALE, MASSACHUSETTS, ASSIGNOR TO DRAPER COMPANY, OF PORTLAND, MAINE, A CORPORATION OF MAINE.

HARNESS-MOTION FOR LOOMS.

No. 817,806.

Specification of Letters Patent.

Patented April 17, 1906.

Application filed February 13, 1905. Serial No. 245,453.

To all whom it may concern:

Be it known that I, CHARLES F. ROPER, a citizen of the United States, residing at Hopedale, in the county of Worcester and 5 State of Massachusetts, have invented certain new and useful Improvements in Harness-Motions for Looms, of which the following is a specification.

The present invention consists in certain 10 improvements upon the side-cam harness-motion set forth in Letters Patent of the United States No. 770,116, granted September 13, 1904, to the Draper Company. The 15 present improvements and their relation to the harness-motion of said patent are illustrated in the accompanying drawings, in which—

Figure 1 is a front elevation of a harness-motion embodying the various features of 20 the invention in their preferred form, so much only of the loom being illustrated as is necessary to show the application of the invention thereto. Fig. 2 is a view of one of the metallic heddles carried by the heddle-shaft. Figs. 3 and 4 are detail sectional views taken on the line 3 4 of Fig. 6, the two views showing the cam R, the wheel Q turned to different positions, and hence showing different configurations of the cam R. Fig. 5 25 is a detail view of one of the selector-cams, the sleeve and shaft upon which the cam is mounted being shown in cross-section. Fig. 6 is a side view of the loom. Fig. 7 is a detail horizontal section on the line 6 6 in Fig. 1. 30 Fig. 8 is a detail vertical section on the line 8 8 in Fig. 7. Fig. 9 is a detail view of a cam-lever, the two coupler-bars connected therewith, the reciprocating actuator, and coöperating features, the parts being shown in the 35 positions which they assume during the dwell-of the actuator near the limit of its upward movement, and one of the coupler-bars being in a position to be engaged by the actuator during its downward movement. Fig. 40 45 10 is a detail view of one of the springs which acts upon one of the coupler-bars. Fig. 11 is a face view of the harness-cam from which the reciprocating movements are imparted to the actuator. Fig. 12 is a view similar to 50 Fig. 9, showing the positions which the parts assume when the actuator is at the middle of its downward movement, one of the coupler-bars being engaged by the actuator and the other coupler-bar being held out of engage-

ment therewith by the coöperating projections on the coupler-bars. Fig. 13 is a view similar to Figs. 9 and 12, showing the positions which the parts assume when the actuator is at the limit of its downward movement. Fig. 14 is a detail sectional view 60 taken on the line 14 14 of Fig. 12, illustrating the manner in which the projections on the coupler-bars coöperate to hold one bar out of engagement with the actuator while the other is in engagement therewith; and Fig. 65 15 is a detail section of one of the side bars of the heddle-shaft, showing its relation to its guide and said shaft. Figs. 1, 6, 9, 11, 12, and 13 are drawn to the same scale, while the remaining figures are on larger scales. 70

For the sake of clearness there is illustrated in the drawings only one heddle-shaft and the connections between it and the actuator, it being understood that any desired number of heddle-shafts may be employed. 75

Each heddle-shaft A is carried by two opposite reciprocating links B B and supports a series of metallic heddles C of well-known construction, each having an elongated slot a, through which the cross-bar A extends. 80 The links B are guided vertically by fixed guides D D. As shown in Fig. 7, each guide D is wide enough to guide all of the links and heddle-shafts employed.

The reciprocating links B B at their upper 85 ends are connected to bell-crank levers E and F, which are connected together by a link b. The bell-crank lever F has rolls c and d, which embrace the cam-surface of a pivoted cam-lever G, to the opposite ends of which are pivotally connected coupler-bars H and I. The cam-lever G has a rest e, which locks with either roll d or c. The two coupler-bars H and I are adapted to engage a vertically-reciprocating actuator J, which is located upon 90 a slide K, adapted to slide vertically upon fixed guide-rods f f. Each coupler-bar H and I has a notch g, adapted to coöperate with the actuator J. 95

The actuator-slide K is connected by a pivoted rod V to one end of a link W, which at its opposite end is pivoted to the framework of the loom. Only a portion of this link W is shown, since it is pivoted to the framework of the loom in substantially the same way as is 100 shown in said patent in connection with the corresponding link 50 thereof. This rod V has a slot through which the cam-shaft U of 105

the loom extends. This cam-shaft has at the outer side of the loom beyond the rod V a cam L, with which coöperate rolls x and w, carried by the rod V, this cam L being angularly adjustable upon the cam-shaft U by means of the disk T and bolts v.

The coupler-bars H and I are brought into coöperation with the actuator J by means of automatic selecting devices. Each pair of coupler-bars H and I belonging to one heddle-frame is moved away from the actuator J by means of a single cam-actuated follower M, but each coupler-bar H and I is moved toward the actuator J by its own spring-actuated follower O. Thus in a five-harness loom there would be five of the cam-actuated followers M and ten of the spring-actuated followers O. Each cam-actuated follower M slides horizontally between guide-plates i, fixed to the rods f, and is controlled by a selector-cam N on a sleeve P upon the shaft o, mounted in a fixed bracket p. This shaft o has a beveled gear r, which engages a beveled gear s on a vertical shaft t, having at its lower end a star-wheel Q, which engages with a cam R on the crank-shaft S of the loom. The two coupler-bars H and I are prevented from simultaneously engaging the actuator J by coöperating cams h, with which they are respectively equipped.

The devices as thus far described are substantially the same in their organization and mode of operation as the corresponding devices in the aforesaid patent, No. 770,116, excepting as hereinafter stated.

The first of the present improvements relates to the connections between the actuating-levers E and F and the heddle-shaft A. In said Patent No. 770,116 the heddle-shaft 40 is connected to rectilinearly-moving side bars which are connected to said levers by links. In the present construction the side bars B are themselves links directly pivoted to the respective levers E and F. As shown in Fig. 45 15, each link B has a socket in which the end of the shaft A loosely fits, and the link B has a rocking face on its outer side which comes in contact with the guideway D. This construction is not only simpler than that of said 50 patent, but it obviates any binding of the heddle-links and insures their movement with the minimum friction. The loose connection between the shaft and the links B compensates for the swing of the links due to 55 their direct pivotal connection with the levers E and F.

The second of the present improvements relates to the spring-actuated followers O, which cause the engagement of the coupler-bars H and I with the actuator J and maintain the coupler-bars in coöperation with the selecting-cam N. Each follower O is a bent lever and it is pivotally connected to the loom-frame and has a toe j, which bears against

one of the coupler-bars and at its other end it 65 is engaged by a coiled spring k. Each spring is connected at opposite ends to metallic loops l, one of which is hooked over the corresponding follower O, while the other (see Figs. 7 and 10) is hooked over a fixed finger 70 m. This construction enables coiled springs, such as those at k, to be employed, which maintain their elasticity indefinitely and insure the prompt and certain action of the coupler-bars H and I. The metallic loops l 75 are readily attached to and removed from the follower-levers O and the fixed fingers m, thus facilitating the replacement of springs k in case of need and also facilitating rendering any harness inoperative in case it is desired 80 not to use the same.

I claim as my invention—

1. A harness-motion for looms having, in combination, a heddle-shaft and reciprocating links at opposite ends thereof, a substantially vertical guide for each of said links, and an actuating-lever pivotally connected directly to each of said links.

2. A harness-motion for looms having, in combination, a heddle-shaft and reciprocating links at opposite ends thereof, each link being loosely connected with one end of said shaft, a substantially vertical guide for each of said links, and an actuating-lever pivotally connected directly to each of said 95 links.

3. A harness-motion for looms having, in combination, a heddle-shaft, two actuating-levers therefor, a reciprocating link pivotally connected at one end to one of said actuating-levers and at its other end being loosely connected to one end of said heddle-shaft, each of said links having a rocking face on its outer lower end, and a substantially vertical guide for the lower end of each link which engages said rocking face.

4. A harness-motion for looms having, in combination, a heddle-shaft and actuating coupler-bar therefor, intermediate connections between said heddle-shaft and said coupler-bar, an actuator adapted to coöperate with said coupler-bar, a cam for moving said coupler-bar in one direction and a spring-actuated follower for moving said coupler-bar in the opposite direction, said spring-actuated follower comprising a pivoted lever and a spring acting upon said lever.

5. A harness-motion for looms comprising a coupler-bar in combination with a pivoted follower-lever bearing against said coupler-bar, a fixed finger, and metallic loops adapted to be placed over the ends of said follower-lever and finger respectively, and a coiled spring connecting said metallic loops.
